UNITED STATES PATENT OFFICE.

WILLIAM LODGE, OF CINCINNATI, OHIO.

POWER MACHINE DRILL.

SPECIFICATION forming part of Letters Patent No. 425,438, dated April 15, 1890.

Application filed July 31, 1889. Serial No. 319,348. (No model.)

To all whom it may concern:

Be it known that I, WILLIAM LODGE, a citizen of the United States, residing at Cincinnati, in the county of Hamilton and State of Ohio, have invented certain new and useful Improvements in Power Machine Drills; and I do hereby declare the following to be a full, clear, and exact description of the invention, such as will enable others skilled in the art to which it appertains to make and use the same.

My invention relates to improvements in upright power machine drills or drill presses, and particularly to means for moving and adjusting the work-table.

The object of my invention is to devise means whereby the work-table may be easily and conveniently moved up and down and sidewise by manipulation from the front of the machine.

The invention consists, essentially, in providing a vertical screw for raising and lowering the work-table and providing bevel-wheels and a hand-shaft for operating the device at the front of the press.

Figure 1 is a perspective view of the framing of an upright power-drill or drill-press, showing my improvements applied thereto. Fig. 2 is a side view of the main portions of the framing and other parts with which the improvements are connected. Fig. 3 is a top view of the parts shown in Fig. 2. Fig. 4 shows a detail.

The same letters or numbers refer to the same parts in different figures.

B is the base-plate of the press; P, its post or column; C, a base-collar on the column P; C', a post-collar above the work-table; and A is the table-bracket, which is supported by the boss D, embracing the column P. The bracket A has a boss E at its extremity for the pivot of the table T, and the bracket is made in halves and bolted together and to the column P by means of the bolts 15. A projecting casing 6 is cast integral with the right half of the bracket and of the form shown, and so as to provide housings and framing for the screw and bevel wheels. The screw 1 has a bearing-block 9 secured at each end by suitable means, as a pin or a screw, Figs. 1, 2, and 4. These blocks are fitted to bear and slide against the surface of the drill-column P, and

also by their sides against the collars C and C', as shown in Fig. 1, and they hold the screw and prevent it from turning, so that a nut which is made in common with the bevel 2 55 may be caused to rotate when the handle 17 is turned. The screw plays freely through the casing 6, and the nut-bevel 2 has end bearings above and below against the inner surfaces of the casing, so that rotation of the nut-bevel will raise or lower the casing and the bracket A, to which it is attached.

A shaft 4 extends horizontally along the right side of the bracket A to a convenient point for using a handle, and has one bearing 65 in the casing 6 and another in boss 12, which is supported by an arm 13, cast integral with the bracket A. This shaft projects into the casing 6 and has a bevel 3 fastened thereon by means of a taper pin 7, Fig. 2, driven in a 70 hole 8, Fig. 3, and this bevel 3 engages and drives the nut-bevel 2. By turning the handle 17, Fig. 1, the nut-bevel 2 may be made to run up or down on the stationary screw 1, and thus raise or lower the bracket A and its table 75 T. The handle and shaft 4 being free, the table may be turned about the column P by pushing it sidewise without disturbing the vertical adjustment of the table. The nut-bevel may be placed above or below the bevel 80 3; but the machine will be more compact when it is placed above the bevel 3. Fig. 2 shows the nut-bevel 2 so placed. In Fig. 3 the nut-bevel is placed below and to show such modification, but more particularly to show plainly 85 the face of the teeth of one of the bevels in some one figure.

I claim—

1. In a power machine drill, the combination of the main-frame column, a table-bracket 90 mounted and turning thereon, an upright screw held against rotation by suitable means, a rotating nut suitably housed and supported by the table-bracket and working on the said screw, bevel-wheels for operating the nut, and 95 suitable means for driving the bevels, substantially as set forth.

2. In a power machine drill, the combination of the main-frame column, a table-bracket mounted and turning thereon, a screw held 100 against rotation and vertical by attached end guiding and sliding bearing-blocks arranged

to bear against the surfaces of the drill-column, a rotating nut suitably housed and supported by the table-bracket and working on the said screw, bevel-wheels for operating the 5 nut, and suitable means for driving the bevels, substantially as set forth.

3. In a power machine drill, the combination of the main-frame column, a table-bracket mounted and turning thereon, an upright 10 screw held against rotation by suitable means, a rotating nut and attached bevel running together on the said screw, the nut being driven by the bevel, another bevel driving the first and a shaft driving the second bevel, suitable 15 bearings and housings being provided for these parts in connection with the said table-bracket, substantially as set forth.

4. In a power machine drill, the combination of the main-frame column, a table-bracket

mounted and turning thereon, an upright 20 screw held against rotation by suitable means, a rotating nut on the screw, a bevel-wheel on the same screw and attached to the nut, a shaft supported under the table, and a second bevel on the inner end of this shaft engaging 25 the first bevel, the bevels and nut being housed in a case cast integral with the table-bracket and the screw and the bevel-shaft having bearings in the same case, the table being raised and lowered by means of the nut, the 30 connected bevels, and bevel-operating shaft, substantially as set forth.

In testimony whereof I now affix my signature in presence of two witnesses.

WILLIAM LODGE.
